EXPANDING REAMER

Filed June 2, 1928

UNITED STATES PATENT OFFICE

FREDERICK C. EISENMANN, OF PHILADELPHIA, PENNSYLVANIA

EXPANDING REAMER

Application filed June 2, 1928. Serial No. 282,375.

The object of this invention is to devise a novel and simplified construction of an expanding reamer wherein the reaming plates can be adjusted without taking the reamer 5 apart.

A further object is to devise a novel and simplified construction of a reamer wherein the reamer plates are adjusted by means of a cone having in threaded engagement with it 10 an adjusting member which overhangs the plates and which is accessible when the reamer is assembled.

With the above and other objects in view as will more clearly hereinafter appear, my 15 invention comprehends a novel expanding reamer.

It further comprehends a novel construction of an expanding reamer wherein the body portion is provided with a longitudinally 20 adjusting cone which is accurately guided therein and which is threaded to receive an adjusting rod having a collar to overhang the reaming plates and provided with a nut in threaded engagement with the 25 body portion and retaining said actuating rod at all times in its operative position.

Other novel features of construction and advantage will hereinafter more clearly appear in the detailed description and the appended claims.

For the purpose of illustrating the invention, I have shown in the accompanying drawings a typical embodiment of it, which, in practice, will give reliable and satisfactory 35 results. It is, however, to be understood that this embodiment is typical only and that the various instrumentalities of which my invention consists can be variously arranged and organized, and that the invention is not limited to the precise arrangement and organization of these instrumentalities as herein set forth.

Figure 1 is a longitudinal section of an 45 expanding reamer embodying my invention, a portion of the shank being shown in elevation.

Figure 2 is a section on line 2—2 of Figure 1.

Figure 3 is a plan view of the reamer with

the plates and their fastening means removed.

Figure 4 is an end view of Figure 3.

Figure 5 is a plan view in detached position of the actuating member.

Figure 6 is a plan view in detached position of the cone.

Figure 7 is an end elevation of an end cap employed.

Figure 8 is a section on line 8—8 of Figure 7.

Figure 9 is an end view of an abutment nut.

Figure 10 is a section on line 10—10 of Figure 9.

Figure 11 is a side elevation of one of the reaming plates.

Similar numerals of reference indicate corresponding parts.

Referring to the drawings:—

1 designates the body portion of an expanding reamer embodying my invention. The body portion is provided with a rearwardly extending cylindrical shank 2 which terminates in a polygonally shaped extension 3.

The body portion is provided with the longitudinally extending slots 4 which are adapted to receive the reaming plates 5, the outer faces of which are straight while the inner faces are rearwardly inclined as at 6.

The ends of the plates preferably converge outwardly or slightly tapered as indicated at 7. The body portion is provided with an aperture or bore 8 which, at its rear portion, merges into a cylindrical aperture 9, and the wall of the bore 8 at its forward end is threaded as at 10.

11 designates a cone longitudinally adjustable in the bore 8 and provided with a cylindrical extension 12 at its rearward end which accurately fits the cylindrical extension 9. The cone 11 is provided with an internally threaded aperture 13 which opens at its forward end and which is adapted to receive a threaded rod 14 which forms an actuating or adjusting member for the cone 11 and thereby for the plates 5.

The adjusting member is provided with a collar 15 which bears against the forward

ends of the knife plates and which is secured in position by means of a nut 16 engaging the threads 10 of the body portion and provided with the spanner receiving openings 17.

5 The rear face of the nut 16 is recessed as at 18 to receive the collar 15. The nut 16 is apertured as at 19 to permit the forward cylindrical extension 20 of the adjusting member to pass therethrough, and the forward end is preferably provided with a slot 21 adapted to receive a tool, such as for example, a screw driver, for effecting its rotary adjustment.

15 The body portion 1 is externally threaded as at 22 to receive a clamping nut 26 which bears against the rear ends of the reaming plates 5. The body portion 1 is also externally threaded at its forward end as at 23, in order to adapt it to receive a cap nut 24 which 20 is internally threaded. This cap nut 24 overhangs the abutment member formed by the nut 16 and is apertured as indicated at 25 in order to permit the extension 20 of the adjusting member to pass therethrough.

25 The cylindrical extension 12 of the cone 11 is prevented from rotation during its adjustment by means of a screw 27 carried by the shank 2 of the body portion and extending into a longitudinally extending slot 28 in the cylindrical portion 12.

30 I also preferably secure to the cylindrical extension 20 of the adjusting member by means of a fastening device, such as for example the pin 29 illustrated, a washer 30, so that the adjusting device is locked with respect to the nut 16. It will be seen that the adjusting device is thus permitted to revolve without longitudinal movement.

Assuming now that the reamer is in assembled condition and it is desired to adjust the reaming plates, one of the nuts 26 or 24 is loosened, and the adjusting member is turned in the proper direction to cause the threaded rod 14 to move the cone 11 forward-45 ly or rearwardly and then the nut which has been loosened is tightened, so that the reaming plates will be rigidly clamped in the position to which they have been adjusted.

50 Special attention is directed to the fact that the adjusting member is always accessible without taking the reamer apart, as the end 20 extends forwardly into such position that it can be actuated by a desired type of operating tools, such as for example, a screw driver.

My present invention can be economically manufactured and any parts which are subjected to wear may be readily replaced.

55 The present construction of reamer provides a large range of adjustment and the reaming plates can be readily removed when it is desired to sharpen them or to replace them. It will also be apparent that the cones 11 have a different taper from that illustrated and may be substituted for the

one illustrated in the drawings. My present construction of reamer is of special advantage since it can be made in small sizes and still have the requisite strength to accomplish the work for which it is intended.

70 In some cases, it is preferable to provide the shank 12 with the slot or key-way 27 into which extends a screw 28 carried by the body portion of the reamer, so that the cone will have a rectilinear movement during its 75 longitudinal adjustment without any relative rotation with the body portion.

It is also advantageous to employ, in some cases, a washer 29 fixed to the extension 20 by means of a pin or equivalent fastening 80 device 30, and the nut 16 is preferably recessed to receive such washer. This maintains accurate alignment of the adjusting member at all times.

85 It will now be apparent that I have devised a new and useful expanding reamer which embodies the features of advantage enumerated as desirable in the statement of the invention and the above description, and while I have, in the present instance, shown 90 and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:-

100 1. In an expanding reamer, a body portion having blade receiving slots and having a shank provided with an opening through one end and of reduced diameter at its rear end, a cone slidable in said opening and having a rearwardly extending cylindrical extension to fit the reduced diameter of said opening, means common to said body portion and cylindrical extension to prevent their relative rotation, blades in said slots having their inner faces inclined throughout their length, a cone adjusting member in threaded engagement with said cone and having means abutting against the forward ends of said blades, a nut in threaded engagement with said body portion and bearing against the forward ends of said blades, and a nut in threaded engagement with said body portion and bearing against the rear ends of said blades to contribute to retain 110 them in their locked position.

115 2. In an expanding reamer, a body portion having blade receiving slots and having a shank provided with an opening through its forward end and of reduced diameter at its rearward end, a cone slidable in said opening and having at its rear end a cylindrical extension to engage the reduced diameter of said opening, and provided with a longitudinally extending slot, a fastening 120

device carried by said shank and extending into said slot, reaming blades in said body portion slots and having their inner faces inclined throughout their length to engage said cone, a cone adjusting member in threaded engagement with said cone and having a collar abutting against said blades, a nut in threaded engagement with the outer wall of said bore and forming an abutment for said collar, said cone adjusting member extending through said nut into a position accessible to the operator, the end faces of said blades inclining outwardly and towards each other, and forward and rear nuts on said body portion conforming to and engaging the inclining portions of said blades to secure them in clamped position.

FREDERICK C. EISENMANN.
